CLAIM

We claim the ornamental design for a motor of a vehicle, as shown and described.

DESCRIPTION

FIG. 1 is a left side elevation view of a vehicle (e.g., a motorcycle) having a motor according to the invention. FIG. 2 is a right side elevation view of the vehicle of FIG. 1.

FIG. 3 is a perspective view of the vehicle of FIG. 1.

FIG. 4 is a front elevation view of the vehicle of FIG. 1; and, FIG. 5 is a bottom view of the vehicle of FIG. 1.

The broken lines showing portions of the motorcycle are for the purpose of illustrating environmental structure and form no part of the claimed design.
